UNITED STATES PATENT OFFICE.

FLORENCE P. SMALLEY, OF LOS ANGELES, CALIFORNIA, ASSIGNOR TO BULLOCK'S INC.,
OF LOS ANGELES, CALIFORNIA, A CORPORATION OF DELAWARE.

DESIGN FOR WRAPPING PAPER FOR PAPER BOXES.

Application filed October 11, 1928. Serial No. 28,453. Term of patent 3½ years.

To all whom it may concern:

Be it known that I, FLORENCE P. SMALLEY, a citizen of the United States, residing at Los Angeles, in the county of Los Angeles and State of California, have invented a new, original, and ornamental Design for Wrapping Paper for Paper Boxes, of which the following is a specification, reference being had to the accompanying drawing, and forming part thereof.

The figure is a plan view of a fragment of wrapping paper, showing my new design. The repeat unit of the design is indicated on

the drawing as contained within the angles *aa—bb* and *cc—bb*, which unit is repeated in the relation illustrated by extension of the design beyond the same.

The individual figures are embodied in the design with contrasting colors.

I claim:

The ornamental design for wrapping paper for paper boxes, as shown and described.

Signed at Los Angeles this 20th day of September, 1928.

FLORENCE P. SMALLEY.
